UNITED STATES PATENT OFFICE.

LAURITZ W. ANDERSEN, OF WATERBURY, CONNECTICUT.

SHADE HOLDER OR SUPPORT.

1,305,985.

Specification of Letters Patent. Patented June 10, 1919.

Application filed May 11, 1917. Serial No. 167,920.

To all whom it may concern:

Be it known that I, LAURITZ W. ANDERSEN, a citizen of the United States, residing at Waterbury, in the county of New Haven 5 and State of Connecticut, have invented a certain new and useful Improvement in Shade Holders or Supports, of which the following is a full, clear, and exact description, reference being had to the accompanying drawings.

This invention is a novel construction of shade holder, the object being to provide an exceedingly simple form of holder which will support the shade or glassware from 15 the interior, and which will completely eliminate the use of screws and threaded appliances heretofore employed in connection with shade rollers.

Another object of the invention is to provide the shade holder which can be used in connection with any type of socket, and various forms of socket covers, and which will be thoroughly safe when once adjusted in position.

25 Broadly speaking, the invention consists of a supporting flange adapted to rest at its inner edge upon the ferrule of the ordinary incandescent lamp and support a shade upon the outer edge thereof, the shade holder being properly positioned for its 30 functions by the attachment of the incandescent lamp to its socket.

The invention consists also in certain details of construction hereinafter fully described and pointed out in the claims.

In the drawings forming a part of this specification Figure 1 is a sectional perspective illustrating the practical application of my invention;

40 Fig. 2 is a similar view showing a slightly different construction of socket shell cover;

Figs. 3 and 4 are similar views showing enveloping rings instead of socket shell covers for enveloping the upper edge of the 45 glassware or shade;

Fig. 5 is a sectional view showing the manner of arranging and securing my improved construction of shade holder;

Fig. 6 is a detail perspective view of the 50 shade holder removed; and

Fig. 7 is a slight modification of the same.

The incandescent lamp A and socket B are of the usual or any approved construction, and the incandescent lamp is made 55 with the usual threaded ferrule C which screws into the end of the socket B.

My improved shade support consists of a centrally apertured plate, or annular flange D, the central opening of which is of such size as to pass freely over the threaded portion of the lamp ferrule but rest at its inner edge upon the shoulder at the end of said ferrule as shown and this inner edge of the flange is cut away or notched as shown at D' in order to accommodate the small drop of solder A' that is present in incandescent lamps at this point. If desired, two, three, or four notches D' may be made in order to provide for greater flexibility at the center of the flange or plate. 70 The shade supporting flange D is provided with an annular bead or shoulder D² intermediate its inner and outer edges, and the outer portion of the flange, or that portion beyond the annular bead or shoulder, is split or slit radially as shown at D³ in order to provide a scalloped outer edge, and the shade or glassware E is adapted to rest upon this scalloped edge as most clearly shown; it being understood that the shade 80 supporting flange D is first placed over the ferrule of the lamp within said shade, and as said lamp is secured into the socket the shade supporting flange will be firmly secured between the shoulder of the ferrule 85 and the end of the socket. At the same time the outer edge of this shade supporting flange will be brought into supporting contact with the interior of the shade or glassware, and hold said shade properly positioned about the incandescent lamp. 90

Any suitable construction of socket shell cover may be employed, such as the complete shell F illustrated in Fig. 1, or the partial cover G illustrated in Fig. 3, in which the upper edge of said cover contacts with the upper bead of the socket shell while the lower edge of the cover envelops the upper end of the shade or glassware. 95

Instead of a socket shell cover such as illustrated in Figs. 1 and 3, a ring H' may be employed as shown in Fig. 2, the upper edge of said ring being curved over and inward as shown at H³ in order to engage the lower bead of the socket and hold the ring in enveloping engagement with the upper end of the shade or glassware. 105

In Fig. 4 the ring H² is of a plain type and merely engages the bead at the lower end of the socket and envelops and protects the upper end of the shade or glassware. 110

- My improved construction of shade support is preferably employed in connection with socket shell covers or rings but it is obvious that it could be employed without 5 such devices, and in Fig. 5 I have shown my improved construction of shade support arranged in connection with the ordinary lamp, socket and shade, the socket shell cover or ring being omitted.
- 10 If desired the scallops can be alternately upset in order to accommodate varying sizes or shapes of glassware and this staggering of the scalloped edges also materially facilitates ventilation.
- 15 A shade support constructed as herein shown and described completely eliminates the use of screws in connection with socket shell covers, or spiders connected to said socket shells; and also eliminates the use of 20 interior shade supports requiring specially constructed coöperating socket shell covers.
- It is obvious that various changes in shape and configuration can be made without departing from the broad principle of my invention as defined by the appended claims. 25
- Having thus described my invention, what I claim is:
1. As a new article of manufacture a metallic shade support adapted to be arranged upon the interior of a shade, said support being circular in form and having a central opening, said opening being of a size and shape to engage the shoulder of the ferrule of an incandescent lamp. 30
  2. As a new article of manufacture a metallic shade support adapted to support a shade from the interior, said support consisting of an annular ring, the inner edge of which is of a size and shape to engage 35 the shoulder of an ordinary incandescent lamp ferrule, the outer edge of said ring being in a plane lower than the inner edge.
  3. As a new article of manufacture a lamp shade support comprising an annular member the inner portion thereof being adapt- 40
  - 45

ed to fit upon the shoulder of a lamp ferrule, the outer laterally projecting portion being adapted to engage a lamp shade, said outer laterally projecting portion being resilient.

50

4. The combination with a socket and lamp having a shouldered ferrule, of a shade support comprising an inner portion adapted to engage the shoulder upon the lamp ferrule, the outer laterally projecting portion thereof being adapted to engage the interior of a lamp shade and an annular member adapted to envelop the upper end of said shade, the inner portion of said enveloping member being adapted to engage 60 a bead of the lamp socket.

55

5. The combination with a socket, lamp having a shouldered ferrule and shade, of an annular cover adapted to surround said socket and envelop the upper end of said shade and an annular member interposed between the lamp and socket, the interior portion of said annular member resting upon the shoulder of the lamp ferrule, the outer portion of said annular member extending laterally outward and engaging the lamp shade upon the interior, said annular member being clamped between the shouldered end of the lamp ferrule and the end of 70 socket.

75

6. As a new article of manufacture a metallic shade holder circular in form and having a central circular opening, said circular opening having a notch, said holder being adapted to be arranged upon the interior of 80 a shade, the outer edge of said holder contacting with and supporting said shade, the inner edge of said holder contacting with the shouldered ferrule of an incandescent lamp.

In testimony whereof, I hereunto affix my 85 signature in the presence of two witnesses.

LAURITZ W. ANDERSEN.
